Primary Examiner — Cynthia Ramirez(74) *Attorney, Agent, or Firm* — Calfee, Halter & Griswold LLP(57) **CLAIM**

The ornamental design for a faucet hub, as shown and described.

DESCRIPTION

FIG. 1 is a perspective view of a faucet hub of the new design; FIG. 2 is a front elevational view of the faucet hub of the new design, the rear elevational view being a mirror image thereof;

FIG. 3 is a left side elevational view of the faucet hub of the new design;

FIG. 4 is a right side elevational view of the faucet hub of the new design;

FIG. 5 is a top plan view of the faucet hub of the new design; and,

FIG. 6 is a bottom plan view of the faucet hub of the new design.

The portions of the Figures shown in broken lines are not part of the claimed design and are for illustration only.
